Des. 212,945
Patented Dec. 17, 1968

212,945

LEVEL WIND AUTOMATIC TROUT REEL

Earle D. Clickner, Kalamazoo, Mich., assignor to Shakespeare Company, Kalamazoo, Mich., a corporation of Michigan

Filed Sept. 15, 1967, Ser. No. 8,606

Term of patent 14 years

(Cl. D22—25)

FIG. 1

FIG. 2

FIG. 3

FIG. 4

FIG. 5

FIG. 6

FIG. 1 is a top plan view of the reel, showing my new design, the line guide being shown in this position in FIGS. 1 and 2 only.

FIG. 2 is a bottom plan view of the reel.

FIG. 3 is an elevational view taken from the front showing the line guide in another position.

FIG. 4 is an elevation view taken from the rear.

FIG. 5 is a side elevational view.

FIG. 6 is a side elevational view taken from the other side of the reel.

I claim:

The ornamental design for a level wind automatic trout reel, substantially as shown and described.
